UNITED STATES PATENT OFFICE

MARTIN FOX, OF CHICAGO, ILLINOIS, ASSIGNOR TO THE SENG COMPANY, OF CHICAGO, ILLINOIS

METAL FIXTURE FOR TYPEWRITER DESKS

Application filed April 8, 1931. Serial No. 528,689.

My invention is an improvement in typewriter desks of the well known construction in which the platform for the typewriter is supported by opposite pairs of link-connected bell crank levers carried by plates slidable on rails in a compartment so as to provide for housing the typewriter in its lowermost position and for elevating the same to position for use in front of the desk, the lifting of the platform and typewriter being assisted by spiral springs interposed between the rear bell crank lever and an arched bar connecting the plates and forming a part of the carriage.

In the operation of swinging typewriter supports of this general construction the bell crank levers are locked by weighted pawls cooperating with the rails in the horizontal movement of the carriage, the forward movement of the latter to released position of the pawls being stopped by engagement of the front rollers and forward ends of the plates with the corner posts of the compartment which are recessed to receive said rollers and the forward ends of the plates and the repeated striking of these metal parts against the corner posts results in tearing out the wood as well as causing stress on the roller. Furthermore, the operation of a gravity pawl in automatically engaging and releasing the bell crank levers is not reliable to the extent required for the effective manipulation of the platform.

It is the principal object of my invention therefore to improve the construction of the metal fixtures of a typewriter desk of this character to increase the simplicity of construction for economy in production and reliability in operation; all as hereinafter set forth and more specifically pointed out in the appended claims.

In the accompanying drawings:

Figure 1 is a vertical longitudinal sectional view through the rear portion of a typewriter desk constructed in accordance

with my invention, the platform for the typewriter being in housed position.

Fig. 2 is a side view with the compartment broken away to show the metal fixtures controlling the operation of the platform, the carriage being near the limit of its forward movement from housed position.

Fig. 3 is a similar view with the carriage at the limit of its forward movement.

Fig. 4 is a detail perspective view of one of the side plates of the carriage.

Fig. 5 is an edge view thereof.

Figs. 6 and 7 are like views of the locking pawl.

The typewriter desk to receive the swinging platform is constructed to provide a compartment 10 in which the typewriter is housed, said compartment having front corner posts 11, 11 and rear corner posts 12 to which the sides 13, 13 and back wall 14 are attached, the front of the compartment being closed by a door (not shown) if so desired. Attached to the front and rear corner posts are horizontal rails 15, 15 supporting the carriage comprising side plates 16, 16 connected at their rear ends by an arched crossbar 17, the said plates having grooved rollers 18, 19 at opposite ends thereof cooperating with pins 20, 21 at opposite edges of the plates from the rollers respectively for properly supporting the carriage in sliding engagement with the rails, and to these plates are pivoted bell crank levers 22, 23 the shorter members of which are connected by a link 24 while the longer members are pivotally connected to a platform 25 on which the typewriter is supported, it being noted by reference to Figs. 1 and 2 that said longer members of the bell crank levers depend from the side plates of the carriage in the lowered position of the platform for housing the typewriter and swing forwardly and upwardly in elevating the platform and typewriter in position for using the latter, and that the

platform for the typewriter and swing forwardly and upwardly in elevating the platform and typewriter in position for using the latter, and that the

lifting movement of the platform is assisted by means of a pair of spiral springs 26, 26 connected at one end to the arched bar 17 and at the other end to a crossbar 27 extending 5 between the longer members of the bell crank levers at the rear end of the carriage.

For pivotally connecting the outer ends of the longer members of the bell crank levers to the platform metal strips 28 are screwed to 10 the opposite edges of said platform and each plate is provided with an upstanding tongue 29 which is adapted to engage a fixture 30 attached to the front corner posts for holding the platform in elevated position as shown 15 in Fig. 3 of the drawings, said fixture being the conventional form of catch.

For locking the bell crank levers in the lowered position of the platform when it is being moved to and from housed position in 20 the desk compartment pawls 31 are pivoted at 31a to the outer sides of the plates 16 and the projecting hook of each pawl is adapted to engage a pin 32 on the bell crank lever 22, said pawl being automatically released by 25 the tail-piece 33 entering a recess 34 in the underside of the rail at the limit of the forward movement of the carriage carrying the platform. The pawl is shaped so as to be pivoted at the outer side of the plate 16 with 30 a lateral extension under the same adjoining the hook which engages the pin on the bell crank lever, and in the present instance the pawl is actuated by a short spiral spring 35 attached at its upper end to an apertured ear 35 projecting from the inner side of the plate with the lower end of said spring formed 40 into a hook passed through an aperture 37 (Fig. 7) in the offset portion of the pawl. The pawl is limited in its downward movement by a lug 38 projecting from the plate, and both the aforesaid apertured ear and stop-lug are stamped from the plate.

The forward ends of the rails 15 are let 45 into recesses 39 in the front posts 11 of the desk, said recesses being adapted to receive the forward ends of the side plates of the carriage, it being noted that the bell crank levers are spaced from said plates by reason of the outwardly stamped bearings 40 which 50 also permit of the connecting link 24 being located between the plate and bell crank levers, and to prevent contact of the rollers 18 with the corner posts a laterally projecting stop member 41 is bent from each plate. 55 This arrangement therefore provides substantial stop members at opposite sides of the platform which abut against the corner posts at one side of the recesses receiving the ends of the plates thus entirely relieving the rollers of any stress and also preventing the ends of the plates of the carriage from injuring the wood. Furthermore, inasmuch as the front rollers 18, 18 are disposed away from the corner posts in the forward position of 60 65 the carriage and the aforesaid stop members

engage the corner posts at one side of the recesses 39 obviating the necessity of providing recesses for the rollers as required when the movement of the carriage is limited by said rollers and ends of the plates, it is therefore apparent that but a single recess is required to be cut into each corner post. This improvement in addition to actuating the pawl by means of a spring and limiting its locking movement simplifies the construction 70 and provides for a smooth and reliable operation of the mechanism which will increase the durability of the several cooperating parts.

The operation is similar to that of typewriter desks of this general construction, that is to say in moving the platform and typewriter carried thereby from housed position within the compartment to elevated position for use in front of the desk the platform is grasped and moved forward sliding the carriage on the rails until the stops 41 projecting from the side plates strike the corner posts at which time the forward ends of said side plates enter the recesses for the advanced position of the parts and the tail-piece of each pawl entering the recess in the lower edge of the rail and hook members of the pawls are thereby released from engagement with the bell crank levers permitting 80 them to swing on their pivots for the lifting of the platform to elevated position where it is held by engagement of the tongue 29 with the catch 30, and in this position the longer members of the bell crank levers are substantially perpendicular to their pivots for firmly supporting the typewriter in position for use. The pawls are yieldingly but positively held in released position by means of the springs 35 so that in housing the typewriter 85 the lowering of the platform will cause the pins 32 on the bell crank levers 22 to engage the pawls which swing on their pivots until the rear ends thereof strike the lugs 38 and the tail-piece is on a horizontal plane immediately below the rails so that said pawls will be engaged by the lower edges of the rails and thereby maintain the bell crank levers locked during the movement of the platform 90 into and out of the compartment of the desk. 100

I claim:—

In combination with a typewriter desk having a compartment with corner posts at its forward end and recesses at the inner side of said posts, of supporting rails at opposite sides of the compartment with the ends of said rails secured in the bottom of the aforesaid recesses, plates slideable on the rails and having grooved rollers at the front and rear thereof traveling over the upper and lower edges of said rails, stop members bent outwardly from near the forward ends of the plates and formed integrally therewith to provide lips with flat surfaces in advance of the front rollers which engage the corner 110 120 125 130

posts at one side of the recesses for limiting the forward movement of the sliding plates, and bell crank levers pivoted to the plates for swinging movement and to which the plat-
5 form is pivoted; together with a pawl piv-
oted to the plate and having a tail-piece entering a recess in the rail, a spring for
moving the pawl into engagement with the recess, and a lug struck from the plate and
10 with which the pawl engages for limiting the movement of the same in one direction, said pawl cooperating with a pin on one of the bell crank levers in the lowered position
15 of the platform.
